(57) CLAIM

The ornamental design for a speaker phone, as shown and described.

DESCRIPTION

FIG. 1 is a perspective view of the speaker phone

FIG. 2 is another perspective view thereof.

FIG. 3 is a front view thereof.

FIG. 4 is a back view thereof.

FIG. 5 is a side view thereof.

FIG. 6 is the other side view thereof.

FIG. 7 is a top view thereof; and,

FIG. 8 is a bottom view thereof.

The features shown in broken lines depict portions of the speaker phone that form no part of the claimed design. *The portions of the design located with the dot-dash boundary line in FIGS. 1 and 3 form no part of the claimed design.*

1 Claim, 6 Drawing Sheets

Matter enclosed in heavy brackets [ ] appears in the original patent but forms no part of this reissue; matter printed in italics indicates the additions made by reissue.
